ATTORNEY

UNITED STATES PATENT OFFICE.

ANTOINE B. PINARD, OF SAN JOSE, CALIFORNIA.

MUTE.

Application filed February 25, 1924. Serial No. 694,949.

This invention relates to improvements in mutes for brass instruments, especially cornets, trombones and the like.

One object of the invention is to provide 5 a device of the character indicated whereby the tone may be muted and still retain substantially the same pitch as the open instrument, and which will produce clearer and more harmonious tones than have heretofore 10 been produced by mutes common in the art.

Another object of the invention is to produce a mute of light and rigid construction which will not be affected by moisture or 15 temperature changes, and not likely to lose its shape because of such influences.

The invention also comprehends improvements in the details of construction which are particularly pointed out in the following 20 description and claims.

In the drawing:

Figure 1 is a longitudinal sectional view through a mute embodying my invention.

Figure 2 is an enlarged detail sectional 25 view of a portion of the same.

Referring more particularly to the drawing, I show at 1 the main body portion of the device. This body portion is frustoconical in shape and is built up of superimposed layers of cloth, paper and wood veneer in the order named and with the cloth lining the interior of the body, the three layers being joined with glue under heavy pressure. The layer of cloth is indicated by the numeral 8, the paper being indicated at 9 and the wood veneer at 10.

The tapering main body 1 is adapted to be inserted in the interior of the horn or bell portion of the instrument in which it 40 is to be used, and is spaced a distance therefrom by resilient blocks 2. These blocks 2 are arranged about the exterior of the body 1 as shown and braced by reinforcing strips of wood arranged at right angles thereto 45 within the body 1 as shown at 3.

The mute is open at the smaller end 4 but is completely closed at its larger end by a diaphragm 5. This diaphragm is turned from a single piece of vibratory wood such 50 as selected maple and has a thick annular outer edge where it is mounted upon the body 1 provided with an upstanding annular bead as indicated at 6, this thick edge portion tapering rapidly to the thinner central portion as shown at 7. The main portion of the diaphragm is approximately

five-sixty-fourths of an inch in thickness, and gives forth secondary sound waves of the same pitch as the primary waves entering the small end 4 of the mute. 60

The entire device is thoroughly water-proofed inside and out, and is held in place by the wedging effect of the blocks 2.

When constructed as hereinbefore set forth the mute becomes a resonance chamber in which most of the original sound vibrations are confined, some of the original sound waves, together with the air, escaping through the space between the mute and the instrument formed by the resilient blocks 70 2. The diaphragm 5 is set in vibration by the trapped waves and in turn gives off from its outer surface a secondary set of sound waves which are the ones mostly heard by the auditor. 75

The diaphragm 5 embodies new and original points of construction as hereinbefore pointed out which enables it to give secondary sound waves having the same acoustical characteristics as the primary, but of diminished intensity. 80

What I claim is:

1. A mute for musical instruments comprising a hollow truncated conical body portion built up of superimposed layers of cloth, paper, and wood veneer in the order named and with the cloth on the interior thereof, and having wedging blocks arranged on its exterior surface near its smaller end and being open at said smaller end, the larger end being completely closed by a thin wooden diaphragm having increasing thickness from the center toward the circumference and having a thickened edge provided with an upstanding annular bead 90 presenting an outer surface substantially ogee shaped in transverse cross-section. 95

2. A mute for musical instruments comprising a thin-walled hollow truncated conical body portion having wedging blocks arranged on its exterior surface near its smaller end and being open at said smaller end, the larger end being completely closed, the closure for the large end consisting of a thin wooden diaphragm having increasing thickness from its center to a point adjacent the perimeter thereof and then suddenly thickening to form a relatively thick annular bead about its periphery. 105

In testimony whereof I affix my signature.

ANTOINE B. PINARD.
